ELECTRIC COMPENSATOR

Laurence Batchelder, Cambridge, Mass., assignor
to Submarine Signal Company, Boston, Mass.,
a corporation of Maine

Refiled for abandoned application Serial No.
299,180, October 12, 1939. This application De-
cember 5, 1940, Serial No. 368,655

2 Claims. (Cl. 177—386)

The present application is a division of my copending application Serial No. 299,180, filed October 12, 1939, now abandoned.

The present invention relates to electric compensators particularly to such as are used for the determination of the direction of submarine sound sources. For this purpose a plurality of electroacoustic transducers for producing electrical response upon excitation by compressional waves are mounted at spaced position in a predetermined configuration. A wave impulse arriving from a distant source will, therefore, strike the several transducers or receivers at different instants of time whereby the electrical currents or voltages produced by the said devices will vary in time phase depending upon the angle which the direction of the sound source makes with the surface upon which the receivers are mounted. By progressively varying the phases of the several electric impulses so produced in such a manner as to bring them all into phase, the direction of the sound source can be determined by noting the amount of phase variation required. For this purpose adjustable electrical retardation lines are commonly employed. The output energy of the retardation lines may be connected to an indicating device such as a pair of telephone receivers so that either a binaural or a maximum effect is obtained when the compensator is adjusted to bring all the received impulses into the same phase.

It is usually desirable to be able to use a compensator with either the maximum or the binaural method at will. Moreover, when using the maximum method, it is often desirable to insert a high-pass filter in the circuit since a sharper bearing can frequently be obtained by listening to high frequencies only. In order to provide a simple arrangement for switching the compensator from maximum to binaural, with or without the filter and to equalize the energy in the telephones in the three cases, I provide a method selector switch and accompanying circuits as shown schematically in the accompanying drawing.

The switch itself may be a five-pole, three-position unit whose control bar is indicated at 1. The five poles or movable contacts of the switch are numbered 2 to 6. Each of these makes contact with a set of three stationary studs, A to C for the three switch positions. In position A the telephones are connected to the retardation lines for the maximum method with a filter inserted between the telephones and the retardation lines. In position B the connections are for

the maximum method without the filter but with an attenuator in the circuit. Position C is for the binaural method with an attenuator. The filter is schematically indicated at 7 and left and right attenuators at 8 and 9 respectively. The retardation lines are indicated at 10, only the three output terminals being shown. It will be understood that compensation is effected in groups, the energy from the left group of sound receivers appearing between the terminals 13 and 15 and that from the right group of sound receivers appearing between the terminals 14 and 15. The telephone receivers are shown at 11 and 12.

15 With the switch in position A as shown, the telephones are connected for operation by the maximum method. The outputs of both ends of the retardation lines are therefore connected together and through the filter to the parallel connected telephone receivers. To this end the left output terminal 13 of the retardation lines is connected through the brush 4 and its contact A by the lead 16 to the input terminal 17 of the filter 7. The right output terminal 14 of the retardation lines likewise, through contact 2 and its stud A, is connected to the input lead 17 of the filter. The common terminal 15 of the retardation lines is connected by the lead 18 to the common side of the filter input and to the junction 19 of the two telephones 11 and 12. The output lead 20 from the filter is connected to the studs A of the two movable contacts 5 and 6 which are connected respectively to the remaining terminals of the telephones 12 and 11.

35 In position B of the switch in which the movable contacts 2 and 6 are connected to the center studs numbered B, the filter is eliminated from the circuit. If this were done directly, there would be a great increase in the energy 40 actuating the telephone receivers since the filter eliminates considerable amount. In order to reduce the energy in such a manner that the volume of the output of the telephones will be the same whether the filter is in or out of the circuit, the attenuators 8 and 9 are provided. The attenuators 8 and 9 are chosen of such value that they will produce substantially the same volume reduction as that produced by the filter 7. For the binaural method one of these is connected in each of the telephone circuits while for the maximum method without filter, they are used in parallel.

50 Thus, in position B the left terminal 13 of the retardation lines will be connected, through the switch numbered 4 and its contact stud B,

to the input lead 21 of attenuator 9 whose output lead 22 will be connected through movable contacts 6 to the telephone receiver 11. In a similar manner, the right output terminal 14 of the retardation lines will be connected through the movable contact 2 to the input lead 23 of attenuator 8 and thence by lead 24 to contact 5 and the telephone 12. The contact 3 which is connected to the terminal 14 of the retardation lines serves in position B by means of the lead 25 and the contact 4 to connect the outputs of the two parts of the retardation lines in parallel so that maximum rather than binaural response is obtained in the telephones.

For the binaural method the switches move to position C, in which case no filter is used, but the output of each side of the retardation lines is separately connected to one of the telephones through one of the attenuators. The circuit is as follows: The left terminal 13 through the movable contact 4 and its third position stud is connected by the lead 21 to the input of the attenuator 9 and by the output lead 22 and switch member 6 to the left telephone 11. The right terminal 14 of the retardation lines is, on the other hand, connected through contact 2 and its third position stud to the input lead 23 of attenuator 8 and by the lead 24 to the contact 5 and thence to the right telephone 12.

By means of this arrangement the operator

can readily switch from binaural method to maximum method and for the latter cut the filter in or out of circuit without in any case appreciably changing the volume of the response of the telephones.

Having now described my invention, what I claim is:

1. In a system for determining the direction of a source of compressional waves with the aid of a plurality of spaced receivers and an electric compensator having retardation lines, the combination therewith of a filter, attenuation means, a pair of telephones and switching means for selectively connecting said telephones to said compensator through said attenuation means for binaural listening and for successively switching said telephones for listening by the maximum method with attenuation means without a filter and with a filter without attenuation means.

2. In a system for determining the direction of a source of compressional waves with the aid of a plurality of spaced receivers and an electric compensator having retardation lines, the combination therewith of a pair of telephones, a filter, attenuation means and switching means including means for switching said system from a maximum method with a filter successively to the maximum method with attenuation and the binaural method with attenuation.

LAURENCE BATCHELDER.
